VALVE FACING DEVICE

Ralph D. Sprung, Rosemead, Calif.

Application June 5, 1945, Serial No. 597,639

1 Claim. (Cl. 51—237)

1

The present invention relates to new and useful improvements in grinding machines for facing or refinishing valves of internal combustion engines and the like, and more particularly to a holder for the valve embodying means for moving the valve toward and away from a grinding wheel, and also for adjusting the valve to different angles relative to the grinding wheel, to conform to the angle of the seating face of the valve with the axis of the valve stem.

An important object of the present invention is to provide a valve holder of this character by means of which the valve may be rotated during its engagement with the grinding wheel.

Another object is to provide a device of this character of simple and practical construction, which is efficient and reliable in operation and relatively inexpensive to manufacture, easy to install in operative position on a work bench in front of a conventional form of electric grinder, and which otherwise is well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a side elevational view with parts broken away and shown in section.

Figure 2 is a rear elevational view.

Figure 3 is a fragmentary sectional view taken substantially on a line 3—3 of Figure 2.

Referring now to the drawing in detail, wherein for the purpose of illustration I have disclosed a preferred embodiment of the invention, the numeral 5 designates an attaching plate for the valve holder secured to front and rear rails 6 by means of set screws 7 for lateral adjustment of the plate, the rails 6 being secured to a work bench or the like 8 in a position adjacent a conventional form of motor-driven grinding wheel (not shown).

The plate 5 is formed with a pair of longitudinally extending, spaced-apart guides 9 between which an upstanding base 10 is slidably mounted, the base 10 having laterally projecting flanges 11 underlying the guides 9.

Rising from the base 10 is a bolt 12 on which a U-shaped tool holder 13 is mounted for rotation, the holder 13 being secured in adjusted position by means of a wing nut 14 carried by the bolt.

A sleeve 15 is slidably mounted in the legs of the holder 13, the sleeve being closed at one end

2

by a disc 16 welded or otherwise secured thereto and welded or otherwise suitably secured to the disc is a wheel 17 having a handle 18 for rotating the sleeve in the holder.

To the other end of the sleeve 15 is secured a conventional form of chuck 19 within which a valve stem 20 is secured, the valve stem having the head 21 formed thereon, to be refaced by a motor-driven grinding wheel (not shown) also mounted on the bench 8.

Threaded through the disc 16 is a screw 22 having an operating wheel 23 secured at its rear end and having a head 24 at its front end formed with a conical recess 25 adapted to receive the inner end of the valve stem 20 for centering the valve stem in the sleeve 15 and chuck 19.

The sleeve 15 has a flange 26 suitably secured thereto between the legs of the holder 13 and against which one end of a coil spring 27 is engaged, the other end of the coil spring bearing against the rear leg of the holder 13 to yieldably urge the sleeve 15 forwardly away from the grinding wheel.

An adjusting screw 28 is threaded through the rear leg of the holder 13 with its rear end adapted to abut the disc 16 at the rear end of the sleeve, the adjusting screw having a knurled manipulating wheel 29 for moving the rear end of the screw 28 toward and away from the disc 16 to function as a stop for the forward movement of the sleeve and to maintain the sleeve 15 rearwardly with the beveled edge of the valve head 21 in engagement with the grinding wheel.

A leaf spring 30 attached to the rear leg of the holder 13 engages the wheel 29 of the adjusting screw to secure the latter in its adjusted position.

The holder 13 and base 10 are moved bodily toward and away from the grinding wheel by means of a lever 31 pivoted to one of the guides 9 by means of a pin 32 and having a vertically extending slot 33 adjacent its pivoted end in which a pin 34 carried by the base 10 is received, the holder thus being moved longitudinally in the guide 9 by the manipulation of the lever 31.

To the upper portion of the base 10 is formed a dial plate 35 and to the under side of the holder 13 is secured a plate 36 having a pointer or indicator 37 at one edge thereof cooperating with the markings 38 on the dial plate 35 whereby to indicate the angle of adjustment of the holder 13 on the base 10, so that the holder may be adjusted on the bolt 12 and at different angles in accordance with the angle of the valve head 21.

In the operation of the device, the screw 22 and head 24 are adjusted longitudinally in the sleeve

15 by the wheel 23 in accordance with variations in length of the valve stem 20 which is secured in the chuck 19 at the front end of the sleeve.

The sleeve 15 is then slidably adjusted in the holder 13 by the adjusting screw 28 to bring the seating face of the valve head 21 into proper grinding relation with the grinding wheel.

As the seating face of the valve head 21 is resurfaced by the grinding wheel, the valve is rotated by the handle 18 and wheel 17 attached to the rear end of the sleeve for thus rotating the sleeve in the holder.

The valve holder 13 and base 10 may be moved bodily by the lever 31 in the guides 9 to move the valve head 21 toward and away from the grinding wheel.

It is believed the details of construction, operation and advantages of the device will be readily understood from the foregoing without further detailed explanation.

While I have illustrated and described a preferred construction for carrying out my invention, it is apparent that various changes in construction and arrangement of the parts may be made without departing from the spirit of the invention.

Having thus described the invention, what I claim is:

A valve holder for use while refacing a valve and including an attaching member, a pair of spaced parallel guides on said attaching member, an upstanding base slidably mounted in said guides, a lever pivoted to one of the guides and operatively engaged with the base for slidably actuating the base, a U-shaped support pivotally mounted on the base for horizontal swinging movement, means for securing the support in pivotally adjusted position on the base, a sleeve slidably and rotatably mounted in the support, means at one end of the sleeve for securing a valve stem therein, an adjusting screw extending longitudinally in the sleeve, a head at the inner end of the screw having a conical recess adapted to receive the inner end of the valve stem to center the valve stem in the sleeve, spring means between the support and the sleeve for urging the sleeve forwardly in the support, an adjusting screw between the sleeve and the support for limiting forward movement of the sleeve, and a hand wheel at the rear end of the sleeve for the manual rotation thereof.

RALPH D. SPRUNG.
